Inventor:

J. A. Eberle,
by Z. K. M. Avery.

UNITED STATES PATENT OFFICE.

JOHN A. EBERLE, OF ST. LOUIS, MISSOURI, ASSIGNOR TO PERFECTION MANUFACTURING COMPANY, OF ST. LOUIS, MISSOURI, A CORPORATION.

UMBRELLA.

No. 918,830.

Specification of Letters Patent. Patented April 20, 1909.

Application filed February 8, 1909. Serial No. 476,746.

To all whom it may concern:

Be it known that I, JOHN A. EBERLE, a citizen of the United States of America, residing in the city of St. Louis and State of Missouri, have invented certain new and useful Improvements in Umbrellas, of which the following is a full, clear, and exact description, reference being had to the accompanying drawings, forming part of this specification.

My invention relates to an improvement in umbrellas more particularly intended for use in wagon umbrellas and whereby the ribs of the umbrella frame are secured to the lower edge of the umbrella.

Figure I is a view partly in elevation and partly in section of the frame and cover of an umbrella with one of my rib connecting devices shown in longitudinal section and another of the devices illustrated in dotted lines, as viewed from the outside of the umbrella. Fig. II is an enlarged elevation of one of the devices viewed from the inside of the umbrella. Fig. III is a longitudinal section taken on line III—III, Fig. II. Fig. IV is an enlarged elevation of one of the devices viewed from the outside of the umbrella. Fig. V is a cross section taken on line V—V, Fig. II. Fig. VI is a view of one of the blanks from which the cover attaching devices are made. Fig. VII is a perspective view of one of the cover attaching devices as it appears previous to its attachment to the cover of an umbrella.

In the accompanying drawings:—A designates the cover of an umbrella and B one of the ribs of an umbrella frame.

My cover attaching devices are attached to the cover of an umbrella at its lower edge at the locations at which the ribs of the umbrella frame are to be present when the cover is stretched over the frame, and each cover attaching device is provided with a socket into which the rib enters and seats.

1 designates the back member of the cover attaching device, and which has extending from it at its upper end a clip tongue 2 that is provided with prongs 3 extending at right angles to the body of the tongue. The back member 1 has formed integral therewith a socket member 4, that extends from one side of the back member and is curled over from said side to the opposite side of the back member, as seen most clearly in Figs. V and

VII, the edge of the socket member being brought to bear upon the back member at its side opposite to that with which the socket member has connection. The socket member 4 has extending from it, at a point approximately midway of its width, a clip tongue 5 which is located at the end of the socket member opposite that facing the clip tongue 2, and at the end of said member which is to serve as the bottom end in the use of my cover attaching device. The clip tongue 5 is bent inwardly from the center of the socket member and transversely of said member, so that it will serve to close the lower end of the socket member to provide a bottom therefor, and this tongue is then bent longitudinally from its portion just mentioned so that it extends in line with the clip tongue 2.

From the longitudinal portion of the clip tongue 5 there extends a portion 6 arranged at a right angle to said longitudinal portion and parallel to the prongs 3. The clip tongue portion 6 terminates in prongs 7 that extend longitudinally of the back member 1 and at a right angle to the clip tongue portion 6.

Before applying my cover attaching devices to the cover of an umbrella, I preferably apply to said cover at the points at which the devices are to be applied reinforcing strips 8, of leather, or other suitable material, and which are applied in part to the outside of the umbrella cover and in part to the inside of said cover.

The cover attaching device which has been constructed from the blank shown in Fig. VI, and which before attachment appears as illustrated in Fig. VII, is secured to the umbrella cover in the following manner: The back of the device is placed against the inside face of the umbrella cover in such position that the longitudinal portion of the clip tongue 5 will rest against the umbrella cover or the reinforcing member applied thereto, and with the portion 6 of said clip tongue occupying a position beneath the lower edge of the cover. The portion 6 of the clip tongue 5 is then bent inwardly to the outer surface of the umbrella cover or the reinforcing member thereon, and the prongs 7 are forced through the cover and reinforcing member whereby the clip tongue 5 is firmly attached to the cover. The upper end of the cover

attaching device is connected to the cover by forcing the prongs 3 of the clip tongue 2 through the cover, and then bending the prongs over so that they will lie parallel with the back member 1, as seen in Figs. I and III.

The herein described umbrella cover attaching device being made in one piece and produced as set forth is of a very simple and durable construction and is so connected to the umbrella cover as to avoid any possibility of its becoming loosened or detached therefrom under strain in the use of an umbrella in which the device is incorporated.

I claim:—

13. 1. An umbrella cover attaching device composed of a single piece of material and comprising a back member, a socket member carried by said back member and curled from one of its sides to the opposite side, a clip tongue at the upper end of said back member, and a clip tongue extending from the lower end of said socket member transversely of the socket member to provide a bottom therefor.
- 25 2. A cover attaching device for umbrellas composed of a single piece of material, comprising a back member, a socket member curled from one side of said back member to the opposite side of said back member, a clip tongue at the upper end of said back member, and a clip tongue extending backwardly from the front of said socket member to said back member to provide a bottom for said socket member, said tongues being provided with prongs whereby the device is attached to an umbrella cover.
- 30

from the front of said socket member to said back member to provide a bottom for said socket member.

3. An umbrella cover attaching device 35 composed of a single piece of material and comprising a back member, a socket member carried by said back member and curled from one of its sides to the opposite side, a clip tongue at the upper end of said back member, a clip tongue extending from the lower end of said socket member transversely of the socket member to provide a bottom therefor, said tongues being provided with prongs whereby the device is attached to an 45 umbrella cover.

4. A cover attaching device for umbrellas composed of a single piece of material, comprising a back member, a socket member curled from one side of said back member to the opposite side of said back member, a clip tongue at the upper end of said back member, a clip tongue extending backwardly from the front of said socket member to said back member to provide a bottom for 50 said socket member, said tongues being provided with prongs whereby the device is attached to an umbrella cover.

JOHN A. EBERLE.
